UNITED STATES PATENT OFFICE.

EDWIN E. WAITE, OF WORCESTER, MASSACHUSETTS, ASSIGNOR OF ONE-HALF TO
WILLIAM B. SCOFIELD, OF WORCESTER, MASSACHUSETTS.

BOOT AND SHOE.

1,015,364.

Specification of Letters Patent. Patented Jan. 23, 1912.

Application filed July 10, 1911. Serial No. 637,591.

To all whom it may concern:

Be it known that I, EDWIN E. WAITE, a citizen of the United States, residing at Worcester, in the county of Worcester and 5 Commonwealth of Massachusetts, have invented a new and useful Improvement in Boots and Shoes, of which the following is a specification, accompanied by drawings forming a part of the same.

10 This invention has for its object an improved method of producing boots and shoes whereby the inner sole is maintained in proper shape to provide a convenient heel seat, and the metallic or other fastenings 15 between the outer and inner soles are prevented from passing through the inner surface of the inner sole. For the accomplishment of this object I employ a novel method of attaching a peculiarly shaped metallic 20 heel seat to the inner sole, permanently concealing the same within the inner sole, so that a smooth surface of leather is provided for contact with the foot, and a sufficient thickness of the inner sole is provided for 25 the attachment thereto of the upper and the outer sole. The inner sole is so shaped as to provide a proper seat for the heel of the foot, and also to prevent any undue pressure of the metallic seat against the foot of 30 the wearer.

Figure 1 represents a central, vertical, sectional view of the heel portion of a boot or shoe embodying my invention. Fig. 2 is 35 a central, sectional view of the heel portion of the inner sole before the insertion of the metallic heel seat. Fig. 3 is a central, sectional view of the heel portion of the inner sole with the metallic heel seat applied thereto. Fig. 4 is a plan view of the metallic heel seat. Fig. 5 is a front view of the heel seat. Fig. 6 is a side view, and Fig. 7 is a central sectional view.

Similar reference characters refer to similar parts in the different figures.

40 The metallic heel seat 1, shown in detached views in Figs. 4 to 7, inclusive, consists of a thin sheet metal plate cut in the form shown in plan view in Fig. 4, with its front edge 2 concave. The length of the 45 heel seat 1 from the rear end 3 to the concave edge 2 is just sufficient to bring the concave edge 2 in alignment with the front edge 4 of the heel 5 of the boot or shoe when the heel seat is inserted in the inner sole. A 50 V-shaped incision is formed in the central portion of the heel seat on the lines 6 and 7, and the inclosed triangular piece of metal 8 is bent downward into the position shown in Figs. 5, 6 and 7, forming a triangular opening 9 in the center of the heel seat. The 55 front or concave edge 2 of the heel seat is bent downward, as represented at 10, to cause the front edge to be embedded in the lower or thicker portion of the inner sole. The 60 metal plate forming the inner sole is dished, 65 forming a concave upper surface 11 and the convex under surface 12 to form a suitable seat for the ball of the heel. The heel seat shaped as above described is then inserted in the inner sole before its application to the 70 last. The application of the heel seat to the inner sole 13 is accomplished by splitting the inner sole from the heel end forward a distance slightly more than the depth of the heel 5, as shown in Fig. 2, forming two portions, a thin portion 14 to provide a cover for the inner or concave surface of the heel seat, and a thicker portion 15 below the heel seat, of sufficient thickness to enable the upper and outer sole to be attached thereto. 75

At the proper distance from the heel end 16 of the inner sole an incision 17 is made through the thicker portion 15 of the inner sole in proper position and of sufficient width to receive the triangular prong 8 80 which is then clenched firmly upon the under side of the inner sole, as shown at 18, Figs. 1 and 3, thereby firmly attaching the metallic heel seat 1 to the under or thicker portion 15 of the inner sole, and drawing the downwardly turned edge 10 of the heel seat into the inner sole. The thin upper portion 14 of the inner sole is then cemented upon the upper or concave surface of the heel seat shaping itself thereto 85 and forming a leather covered contact surface for the heel of the wearer, shaped to correspond to that of the heel seat 1. The triangular opening 9 formed in the center of the heel seat allows nails to be driven through the inner sole into the last for the attachment of the inner sole to the last and allows the upper 19 to be drawn over the edges of the inner sole in the process of 90 lasting, as shown at 20, Fig. 1, thereby shaping the under portion of the inner sole to the dished form of the metallic heel seat. The outer sole 21 is then applied and attached to the inner sole by nails 22 which have their points clenched against the un- 95 100 105 110

der side of the metallic heel seat, as represented in Fig. 1. The heel 5 is then completed in the usual manner.

I am aware that metal plates have heretofore been employed in the manufacture of boots and shoes to provide a surface against which attaching nails may be clenched and also that it has been proposed to attach such metallic plates to the inner or outer soles 10 of boots or shoes by means of prongs integral with the metallic plate. I therefore do not claim either of these features broadly. I am also aware that it has been proposed to insert a temporary metallic 15 plate in the heel portion of the inner sole by splitting the leather to provide for the insertion of the metallic plate which serves the purpose of a clenching plate for the clenching of attaching nails of the outer 20 sole, said clenching plate being removed after the withdrawal of the last.

According to my present invention the metallic heel seat is intended to become a permanent fixture in the boot or shoe in order to give proper shape and bearing surface to the ball of the heel. I therefore make provision for the accurate insertion or registration of the metallic heel seat with the inner sole of the boot or shoe, by providing an attaching prong 8 of sufficient width to hold the metallic heel seat against forward movement, and also to prevent any rocking or swinging movement of the heel seat about the prong, and the 30 accurate registration of the heel seat with the heel portion of the inner sole is secured by forming the incision 17 in the inner sole at the proper distance from the heel end 16 of the inner sole to bring the 35 heel seat in the proper position when inserted in the inner sole. The concave or arched form of the edge 2 together with the dished shape of the metallic heel seat enables it to fit the foot of the wearer between 40 the heel and the shank. The downward inclination 10 of the concave edge 2 removes all possibility of an undue pressure being

brought against the foot or a ridge being formed in the thin covering portion of the inner sole.

50

I claim,

1. In a boot or shoe, a split inner sole, a dish shaped metallic heel seat inserted therein and cemented to the inner portion of said inner sole, with the front edge of said heel seat concave and downwardly turned, and means for drawing the downwardly turned edge of said seat against the outer portion of said inner sole.

2. In a boot or shoe, a split inner sole, a dish shaped metallic heel seat cemented to the inner portion of said inner sole, means for registering said heel seat with the heel portion of said inner sole, and means for attaching said heel seat to the outer portion of said inner sole.

3. In a boot or shoe, a dish shaped metallic heel seat having an outwardly projecting prong adapted to enter the inner sole, an inner sole attached by said prong to the under side of said heel seat, said heel seat having a central opening and a downwardly bent front edge.

4. In a boot or shoe, an inner sole, a dish shaped metallic heel seat, having a central triangular opening and a downwardly projecting triangular prong, with its base arranged transversely to said heel seat, with said prong clenched to the under side of said inner sole and a leather covering for said heel seat.

5. As an article of manufacture, a heel seat consisting of a dish shaped metallic plate, having an inner concave and an outer convex surface, with its front edge concave and downwardly turned, said plate having a central opening, and provided with means for its attachment to the inner sole of a boot or shoe.

Dated this fifth day of July 1911.

EDWIN E. WAITE.
